US0D1045668S

(12) **United States Design Patent** (10) **Patent No.:** **US D1,045,668 S**
(45) **Date of Patent:** **** Oct. 8, 2024**

(54) **DRONE**

(71) Applicant: **Sonin Hybrid, LLC**, Atlanta, GA (US)

(72) Inventors: **Curtis Asa Foster**, Lawrenceville, GA (US); **Mohammed Zijah Abdul Aziz**, Thrissur (IN)

(73) Assignee: **Sonin Hybrid, LLC**, Atlanta, GA (US)

(**) Term: **15 Years**

(21) Appl. No.: **29/747,516**

(22) Filed: **Aug. 24, 2020**

(51) **LOC (14) Cl.** **12-06**

(52) **U.S. Cl.**

USPC **D12/16.1**

(58) **Field of Classification Search**

(57) **CLAIM**

The ornamental design for a drone, as shown and described.

DESCRIPTION

FIG. 1 is a perspective view of a drone according to the present disclosure.

FIG. 2 is a front view thereof.

FIG. 3 is a rear thereof.

FIG. 4 is a left side view thereof.

FIG. 5 is a right side view thereof.

FIG. 6 is a top view thereof; and,

FIG. 7 is a bottom view thereof.

The dashed lines in the figures show portions of the drone that form no part of the claimed design.
